(57) **CLAIM**

The ornamental design for a mobile device picture frame, as shown and described.

DESCRIPTION

FIG. 1 is a perspective front view the mobile device picture frame including the mobile device in broken lines showing the present design.

FIG. 2 is a perspective front view the mobile device picture frame showing the present design.

FIG. 3 is a front view the mobile device picture frame including the mobile device in broken lines showing the present design.

FIG. 4 is a front view the mobile device picture frame showing the present design.

FIG. 5 is a back view of the mobile device picture frame showing the present design.

FIG. 6 is a front view of the back part of the mobile device picture frame showing the present design.

FIG. 7 is a top view of the mobile device picture frame showing the present design.

FIG. 8 is a left side view of the mobile device picture frame showing the present design; and,

FIG. 9 is a right side view of the mobile device picture frame showing the present design.

The broken line showing of the mobile device illustrates the environment of the claimed design and forms no part thereof.

1 Claim, 6 Drawing Sheets
